HANS STAMM, OF ST. GALLEN, SWITZERLAND, ASSIGNOR TO THE FIRM OF ADOLPH SAURER, OF ARBON, SWITZERLAND.

SHORT STRAIGHT-PULL BREECH-ACTION FOR MILITARY HAND-FIREARMS.

1,172,069.

Specification of Letters Patent. Patented Feb. 15, 1916.

Application filed October 27, 1914. Serial No. 868,854.

To all whom it may concern.

Be it known that I, HANS STAMM, a citizen of the Republic of Switzerland, residing at St. Gallen, Switzerland, have invented new and useful Improvements in Short Straight-Pull Breech-Actions for Military Hand-Firearms; and I do hereby declare the following to be a full, clear, and exact description of the invention, such as 5 will enable others skilled in the art to which it appertains to make and use the same, reference being had to the accompanying drawings, and to letters or figures of reference marked thereon, which form a 10 part of this specification.

Straight pull breech action in which the breech bolt, fitted with locking nibs, can be turned by a turning member mounted on it, a so-called "grip", or a rectilinearly movable locking member in the breech frame, in order to effect the locking and unlocking, have already been made known. In these 20 breech action systems the locking nibs are fitted in front on the breech bolt head, owing to which the turning member, the grip or the locking member has to be pushed over the bolt from behind.

In straight pull breech actions in which the breech bolt can be turned by a locking member which moves to and fro in a straight line, spiral grooves must be provided for the purpose of rotating the breech bolt, these grooves being cut in the surface of the bolt, the consequence of which is that 30 the back end of the bolt is very much weakened on the one hand by these grooves, and on the other hand by the principal bore in the breech bolt which serves to receive the striking mechanism or device, and also 35 by a screw-thread outside or inside the back end of the bolt, which serves to receive a nut or guide socket. If this weakened bolt end is furthermore provided on its front face with notches in which, for 40 the purpose of automatically gripping and securing the striking pin, a securing member connected with the latter must move, this weakened notched surface at the rear 45 end of the bolt will rapidly wear away and in course of time lose its shape. Fur-

thermore, the provision of the locking nibs on the front end of the breech bolt involves an extremely long breech mechanism, because behind the locking nibs, directly in front of the loading aperture back supports 55 must also be provided on the breech frame, thus entailing considerable lengthening of the movement of the whole of the breech mechanism when opening and closing it. According to the present invention these 60 drawbacks are to be remedied by arranging the locking nibs on the back part of the breech bolt and making it possible to push the locking member from the front on to the breech bolt so that the rear end of the 65 bolt can without hindrance be made of sufficient strength, and means are further provided to enable the front end of the bolt in the closed position of the breech mechanism, to project only a small amount into 70 the breech frame in front of the loading aperture, so that the breech action and its movements are extremely short.

A constructional example of the invention is illustrated in the accompanying drawings, in which:

Figure 1 is a vertical longitudinal section through the locked breech mechanism after firing a shot. Fig. 2 is a horizontal longitudinal section through the breech action 80 shown in Fig. 1. Fig. 3 is a horizontal section through the breech action in its open and drawn back position. Fig. 4 is a vertical section of a safety device combined with the trigger for securing the breech bolt. Fig. 5 is a section on the line A—B of Fig. 1 with the safety device in side elevation.

As shown, the military firearm possesses a straight pull breech action which is movable in a straight line to and fro in a stationary breech frame 1 rigidly fixed to the barrel 2. The breech action has the rotatable breech bolt 3 which carries at its rear thickened end the two locking nibs 4 (Figs. 1, 4 and 5) provided with transverse steps, 90 and which are in one piece with the breech bolt; also the locking member or locking sleeve 5 pushed on to the breech bolt from the front, which sleeve is movable to and fro on the breech bolt and is provided with 95 100

a handle 6, by means of which the locking sleeve or the entire breech action can be actuated. For receiving the locking nibs 4 when locking the breech mechanism, there 5 are provided at the rear end of the breech frame 1, the two locking recesses 7 formed with rear abutments 8 (Figs. 1 and 4).

In order to impart the necessary rotary movement to the breech bolt for locking and 10 unlocking, the breech bolt is formed with helical grooves 9 into which the locking sleeve 5 projects with corresponding helical ribs 10. The locking sleeve 5 has such 15 longitudinal movement on the breech bolt 3, that when shifted on the bolt it imparts to the latter a quarter turn of 90°, the nibs 4 being turned into the recesses 7 or out of them. The movement of the locking sleeve 20 on the breech bolt is limited in its backward movement on the breech bolt by the stop face 3' on the breech bolt (Fig. 1) and is limited in its forward movement thereon by a nose 11 on the cartridge extractor 12 of the breech bolt, the said nose extending 25 into a recess 5' in the locking sleeve 5 (Figs. 2 and 3).

The locking sleeve 5 is guided by lateral ledges 13 in corresponding longitudinal grooves 14 in the breech frame 1. These 30 grooves 14, in the rear ends of which the nibs 4 can also be guided, are in connection with the recesses 7 so that the nibs can be turned out of the grooves 14 into the recesses and vice versa out of the recesses into 35 the grooves. In order to prevent the complete drawing out of the breech action from the breech frame when opening the breech for the purpose of loading, there is fitted at the rear end of the breech frame 1 a breech 40 holder which consists of a lever 15 mounted at the side of the breech frame, and formed with a nose 16 which projects into the latter, under the action of a spring. There is also provided at the front end of the 45 breech bolt a recess 17, into which the nose 16 of the lever 15 can snap when the breech is open and thus prevent the breech action from being completely drawn out of the frame (Fig. 3).

50 In the breech bolt 3 the striking device is mounted; it consists of the striking pin 18 which carries at its front end the removable tip 19 and at its rear end a head 20 formed with a lateral safety arm 21 (Fig. 2). The striking pin is under the action of the main spring 22 which bears at one end against the striking pin tip 19 and at the other end against a sleeve 23 screwed into the breech bolt 3 (Figs. 1-3). 55 This sleeve has a rear cylindrical socket 24 to receive a safety sleeve 25, which is in turn designed to receive the striking pin head 20. The safety sleeve 25 and the socket 24, which serves as guide for the safety sleeve, have

notches diametrically opposite, *i. e.* angularly displaced by 180° to each other, for receiving the safety arm 21 in the secured and unsecured position of the striking pin, into which notches the arm can be moved after turning through 180°. The notches 65 in the safety sleeve 25 are marked 26 and 27. The notch 27 is shallower than the notch 26 and serves as the securing notch proper for the arm 21 of the striking pin. The notches in the guide socket 24 are only 70 provided to allow the arm 21 to enter the notches in the safety sleeve; they are deeper than the notches 26 and 27 (Figs. 2 and 3).

The sleeve 25 is coupled to the striking pin by means of a stud 28 mounted in it, 80 which projects into a groove 29 in the striking pin head 20. The groove 29 is semi-annular to allow of rotating the striking pin relatively to the safety sleeve; at its end it is made wide enough to permit of drawing 85 back the striking pin in the safety sleeve 25 for the purpose of securing it. A ledge 25' (Fig. 4) provided on the lower face of the sleeve 25 projects into a longitudinal slot in the guide socket 24 and at the bottom of 90 this ledge there is the lug 30 and at the front end of the ledge, the safety nose 31 which, for the purpose of securing the breech bolt 3, works in conjunction with two notches 32 and 33 at an angle of 90° to 95 each other provided at the back end of the breech bolt. The notch 32 is deeper than the notch 33 (Fig. 2) to enable the striking pin to shoot forward with the safety sleeve on firing. The notch 32 on the other hand, 100 in which the nose 31 lies after unlocking the breech bolt, and which is connected with the notch 32 by an oblique surface, serves the purpose of keeping the striking pin in its secured drawn back position. 105

34 is the spring cartridge ejector which is fitted in a vertically movable manner beneath the breech bolt, and for the purpose of ejecting the empty cases of the fired cartridge, enters a groove 35 in the front end 110 of the breech bolt end.

36 designates the cartridge magazine and 37 the removable magazine bottom.

38 designates the trigger, and 39 the sear under the action of a spring, with lug 40. 115 The sear 39 carries at its front end a cheek 41 (Figs. 4 and 5) projecting upward through a hole in the breech frame, and acts in conjunction with one of the locking nibs 4 for securing the breech bolt in the 120 locked position, and at the same time renders it impossible to fire the shot before the breech bolt is completely locked.

42 is the loading aperture (Fig. 3).

The method of handling and the operation of the firearm is as follows: The breech action is shown in Figs. 1 and 2 in the locked position after firing a shot, the lock-

ing sleeve 5 is in its front position on the breech bolt and the safety sleeve 25 projects with the nose 31 into the deeper notch 32 at the back end of the breech bolt, while the safety arm 21 of the striking pin 18 is in the deeper notch 26 of the safety sleeve 25, *i. e.* in the unsecured position. To open the breech mechanism, the locking sleeve 5 is drawn back; this, in the first instance, owing to the helical grooves 9 and the screw pieces 10, causes the breech bolt 3 to turn, that is unlocks the breech action, and owing to the transverse step on the locking nibs 4, the empty cartridge case which has been fired is very much loosened. Toward the end of the releasing movement, the back end of the locking sleeve strikes against the stop surface 3' of the breech bolt and the locking nibs 4 pass out of the recesses 7 in the breech frame into the guide grooves 14, and from this moment the whole breech action is drawn back behind the loading aperture 42 where it is held fast by the lateral breech holder 15, which projects into the recess 17 at the front end of the breech bolt (Fig. 3). At the same moment the cartridge case which was just loosened is thrown out by the ejector 34 provided beneath the loading aperture, and during the return movement of the locking sleeve, *i. e.* during the releasing rotation of the breech bolt, the striking pin 18 is drawn farther back. The last operation is effected by the safety sleeve 25 which is shifted back by the rising sloping surface 35 between the notches 32 and 33 (Fig. 3) at the back end of the breech bolt, engaging the nose 31, which under the pressure of the main spring, snaps into the shallower safety notch 33 at the end of said surface, owing to which the striking pin tip 19 is also drawn away from the cartridge percussion cap and held or secured in this drawn back position. At the same time the breech bolt 3 is in this way prevented from making an unintended further turn. When closing the breech action, owing to the rectilinear forward push of the locking sleeve 5, the breech bolt 3 in the first place forces a fresh cartridge, pressed up from the magazine, into the barrel and at the same time, when the breech action is forced forward, the striking pin lug 30 on the safety sleeve is held by the trigger lug 40 and the main spring 22 put under tension. When the breech bolt 3 strikes behind the cartridge at the back end of the barrel, a mere forward thrust of the locking sleeve suffices to turn the breech bolt again through the helical grooves 9 and the screw pieces 10, and consequently the locking nibs 40 will again reach their locking position in the recesses 7, and the nose 31 on the safety sleeve has been turned out of the shallower notch and will lie opposite the deeper notch 32 at the back end of the breech bolt, into which it will enter when the shot is fired; 65 consequently the firearm is again ready for firing. In addition to this automatic securing of the striking pin and breech bolt during the opening of the breech action, the striking pin 18 can, as already mentioned, 70 be secured by hand even before firing the shot, *i. e.* before opening the breech action, the safety arm 21 on the striking pin being turned over to the other side, *i. e.* drawn out of the deeper notch 26 and shifted into the 75 shallower notch 27 of the safety sleeve 25, owing to which the striking pin tip 19 is drawn away from the cartridge cap and is held in this position by the main spring 22.

In the straight pull breech action above 80 described and illustrated, the arrangement in which the locking nibs are provided at the back end of the breech bolt and the rotary member, *i. e.* the locking sleeve 5 can be thrust from the front over the breech bolt, 85 permits of making the rear end of the breech bolt of sufficient strength without any hindrance, and the front end of the breech bolt need only project by a small amount in front of the loading aperture, into the 90 breech frame. Owing to these measures, a considerable strengthening and shortening of the breech action and mobility of the breech action when opening and closing it for the purpose of loading, are secured. 95 Owing to the strengthening of the rear end of the breech bolt, it is also made possible to utilize the guide sleeve as back support for the main spring and make the rear parts of the striking pin and safety mechanism of 100 sufficient strength. The arrangement of the locking nibs at the rear end of the breech bolt, *i. e.* behind the loading aperture, also allows of fitting the breech safety pieces 4, 105 41, at the most favorable possible point. Owing to the fact that when actuating the trigger, the cheek 41 on the sear 39 can rise up from below, together with the breech nib 4 lying below, the breech bolt is, when the shot is fired, prevented by the cheek 41 from turning back and thus effecting automatic unlocking. If, when the shot is fired the breech bolt should not be fully locked, and therefore the locking nibs not in their proper locking position, it is impossible to 110 pull the sear down to fire the shot, because its cheek 41 cannot then rise into the aperture in the breech frame 1 covered by the lower locking nib, and therefore the firing of the shot when the breech action is not completely locked is prevented, so that the above breech safety arrangement against unlocking of the breech action serves at the 115 same time as an absolutely reliable safety arrangement against firing.

The taking apart and putting together again of the breech action can be effected with great facility owing to the simplicity 120 125

of the design. After drawing the breech action out of the breech frame, the sleeve 23 together with the striking device, are unscrewed from behind out of the breech bolt 3, whereupon the striking pin tip 19 is uncoupled from the striking pin 18 and can now be removed together with the main spring. Hereupon the striking pin 18 is by its arm 21, together with the safety 10 sleeve, drawn from behind out of the guide socket 24 and the entire breech action has thus been taken apart. It is not necessary that the locking sleeve 5 should also be slipped forward over the breech bolt except in the case of general cleaning or greasing. In this case only the spring cartridge extractor 12 is pressed down slightly by its nose 11, whereupon the locking sleeve can straightway be slipped off the breech bolt. 15

20 Putting together is effected in the inverse order with the same ease and simplicity. The striking pin 18 together with the sleeve 25 are pushed from behind into the guide socket 23, 24. Hereupon the main spring 25 is pushed from the front on to the long front part of the striking pin and the striking pin tip is then coupled to the striking pin 18 in front of the main spring. The whole is now screwed into the breech bolt 30 from behind by means of the guide socket, whereupon the breech action can straightway be pushed back into the breech frame.

What I wish to claim is:

1. In a straight pull breech action for firearms, a breech frame, a breech bolt having integral locking nibs on its rear end adapted to engage recesses in the back part of the breech frame, a locking sleeve guided rectilinearly in the latter and on the breech bolt 40 in front of the nibs, and means on the sleeve and bolt for locking the latter in the frame.
2. In a straight pull breech action for firearms, a breech frame, a breech bolt having integral locking nibs on its rear end adapted 45 to engage recesses in the back part of the breech frame, a locking sleeve guided rectilinearly in the latter and on the breech bolt in front of the nibs, means on the sleeve and bolt for locking the latter in the frame, 50 and means on the breech bolt to limit the backward and forward movement of the locking sleeve on the bolt.
3. In a straight pull breech action for firearms, a breech frame, a breech bolt having 55 integral locking nibs on its rear end adapted to engage recesses in the back part of the breech frame, a locking sleeve guided rectilinearly in the latter and on the breech bolt, helical ribs and grooves on the sleeve and 60 bolt for locking the latter in the frame, a spring cartridge extractor at the front end of the breech bolt having a projecting nose engaging a recess at the front end of the locking sleeve, and a stop on the rear part

of the breech bolt to limit the backward movement of the sleeve on the breech bolt. 65

4. In a straight pull breech action for firearms, a breech frame, a breech bolt having integral locking nibs on its rear end adapted to engage recesses in the back part of the breech frame, a locking sleeve guided rectilinearly in the latter and on the breech bolt, said sleeve having helical ribs engaging helical grooves in the bolt for locking the latter in the frame, means on the breech bolt 70 for limiting the backward and forward movement of the sleeve on the bolt, and means to limit the opening movement of the breech action. 75

5. In a straight pull breech action for firearms, a breech frame, a breech bolt having integral locking nibs on its rear end adapted to engage recesses in the back part of the breech frame, a locking sleeve guided rectilinearly in the latter and on the breech bolt, said sleeve having helical ribs engaging helical grooves in the bolt for locking the latter in the frame, means on the breech bolt for limiting the backward and forward movement of the sleeve on the bolt, and a spring 80 actuated member arranged on the frame to engage a recess in the front end of the breech bolt when the latter is near the end of its rearward movement. 85

6. In a straight pull breech action for firearms, a breech frame, a breech bolt having integral locking nibs on its rear end adapted to engage recesses in the back part of the breech frame, a locking sleeve guided rectilinearly in the latter and on the breech bolt, 90 means on the sleeve and bolt for locking the latter in the frame, a sear mechanism, and means for preventing the unlocking of the breech bolt on firing and to prevent the operation of the sear when the breech action is 95 unlocked. 100

7. In a straight pull breech action for firearms, a breech frame, a breech bolt having integral locking nibs on its rear end adapted to engage recesses in the back part of the breech frame, a locking sleeve guided rectilinearly in the latter, and on the breech bolt, means on the sleeve and bolt for locking the latter in the frame, a sear mechanism, and an upwardly projecting member arranged to 110 be moved by the sear into the casing adjacent one of the locking nibs to prevent unlocking of the breech bolt on firing. 115

8. In a straight pull breech action for firearms, a breech frame, a breech bolt having integral locking nibs on its rear end adapted to engage recesses in the back part of the breech frame, a locking sleeve guided rectilinearly in the latter and on the breech bolt in front of the nibs, means on the sleeve and bolt for locking the latter in the frame, means on the breech bolt to limit the backward and forward movement of the locking 120 125

sleeve on the bolt, means to limit the opening movement of the breech action, and means to prevent the unlocking of the breech bolt upon firing and to prevent the 5 operation of the sear when the breech action is unlocked.

In testimony that I claim the foregoing

as my invention I have signed my name in presence of the subscribing witnesses.

HANS STAMM.
